UNITED STATES PATENT OFFICE.

ALBERT R. FOWLER, OF ROCHESTER, NEW YORK, ASSIGNOR OF ONE-HALF
TO LOUIS SCHNEIDER, OF SAME PLACE.

DESIGN FOR A CIGAR-CONTAINER.

SPECIFICATION forming part of Design No. 34,817, dated July 23, 1901.

Application filed June 26, 1901. Serial No. 66,165. Term of patent 7 years.

To all whom it may concern:

Be it known that I, ALBERT R. FOWLER, a citizen of the United States, and a resident of Rochester, in the county of Monroe and State of New York, have invented and produced a certain new and original Design for a Cigar-Container, of which the following is a specification.

As shown in the drawing, the design consists of a substantially rectangular box-like device open on the top and at the upper part of the front having the flat vertical back portion A, connecting at its lower portion with a forwardly-curved part a, which merges into the horizontal bottom portion A'. This bottom portion A' has in the middle thereof the curved recess a', extending inwardly from its front edge, and at each end a sub-

stantially rectangular opening a². The front has two upright portions a³, each curving downward on its upper edge to merge into the edge of the recess a'. The back portion A is higher than the front portions a³. At each end of the design is a flat end portion A², connecting the ends of the back portion A with the ends of the front portions a³. An outwardly-turned horizontal extension A³ extends from the upper edge of each end portion A².

What I claim is—

The design for a cigar-container, substantially as shown and described.

ALBERT R. FOWLER.
